POLISHING MACHINE

William P. Egan, Lynn, Mass.

Application April 26, 1935, Serial No. 18,372

7 Claims. (Cl. 12—77)

This invention relates to a polishing machine, and more especially to a machine or attachment particularly adapted for use in the cleaning and polishing of heels in the finishing of shoes and the like. Heels of different materials and construction require different treatments in the finishing of their exposed surfaces and composite heels require more than one kind of treatment, thus necessitating more than one finishing operation. For example, a leather heel with a rubber toplift thereon requires a light polishing treatment for the leather portion, whereas the rubber toplift requires a heavier cleaning and polishing treatment. One of the objects of my invention is the production of an improved apparatus for performing both these treatments in one operation, thereby greatly reducing the time and cost of such treatments.

In the polishing of heels it is also necessary properly to position the heels relative to the polishing brush, whereby to treat only the surfaces to be finished. This positioning of the heel varies with heels of different dimensions, and to perform the work with greatest accuracy the heel must be positioned both laterally and radially of the brush. A further object of my invention contemplates the provision of improved guiding means or guiding attachment for the heels to be treated, which means can be readily placed and conveniently adjusted relative to the brush to accommodate heels of varying dimensions and which will serve accurately to locate the heels in proper operating position both laterally and radially of the brush.

These and other features of the invention will be best understood from the following description of a preferred embodiment thereof, selected for purposes of illustration and shown in the accompanying drawing, in which

Fig. 1 is a fragmentary view of a heel polishing machine having my improved work guiding means applied thereto;

Fig. 2 is a plan view thereof;

Fig. 3 is a front elevation;

Fig. 4 is a fragmentary sectional view of the guide adjusting means;

Fig. 5 is a fragmentary front elevation of a modified form of the invention; and

Fig. 6 is a fragmentary view of a further modification thereof.

Referring more specifically to the drawing by reference characters, 10 indicates a shaft mounted in bearings 12 supported on a frame 14. Mounted on the shaft directly adjacent to each other are a relatively soft polishing brush 16 and

a coarser cleaning and polishing brush 18. The brush 16 is particularly adapted to the polishing of heels of leather and the like, and the brush 18 is more particularly adapted to the cleaning and polishing of heels of rubber and the like.

Cooperating with the brushes 16 and 18 (Fig. 4) is a guide or stop member comprising a head portion 20 and a rearwardly extending support 21 mounted to slide in and laterally of an arm or bracket 22 (Figs. 1 and 3) secured to the frame by bolts 24. The bracket is provided with a guideway 26 for the member 20—21 and a pin 28 carried by the member extends through a slot 30 in the bracket and carries a collar 32 which serves to hold the member in the guideway. The inner end 34 of the pin engages within a spiral slot 36 in a bushing 38 pinned at 40 to a shaft 42, whereby the member 20—21 is shifted along the guideway upon rotation of the shaft. The shaft may be rotated by means of a handle 44 on its outer end and an expansion spring 46 is provided for preventing free rotation thereof.

It will be noted that the bracket 22 is slotted at 48 whereby it can be adjusted longitudinally and thereby provide an adjustment of the member 20 radially toward and from the brushes. In using the device, the bracket is so mounted that the concave portion 50 of the head 20 is in a position closely adjacent to the periphery of the brushes but preferably free from contact therewith. The lateral position of the bracket (Fig. 4) is such that the head 20 can, by rotation of the handle 44, be adjusted laterally across the periphery of the brushes. Indices 52 and 54 (Fig. 3) may be provided for indicating the lateral position of the head relative to the brushes. The head has a work engaging face 56 on the forward end of the member 20—21 and, as shown in Fig. 3, when the member is set to zero position this face coincides with the line between two brushes. The member may be adjusted to any desired position merely by rotating the handle 44 and, due to the action of the spring 46 and the steep character of the slot 36, will normally remain in such position during the polishing operations. If desired, however, the member may be locked in position by tightening the nut 58 on the pin 28.

When it is desired merely to polish heels such as the leather heel 60 shown in Fig. 2, the member 20—21 is set to the zero position, whereby only the polishing brush 16 is exposed forwardly of the face 56. The heel may thereupon be quickly polished by bringing it laterally against

such face and holding it in contact with the brush 16. In polishing curved surfaces of heels, it is usually desirable also to locate the heel radially of the brush and for this purpose I have 5 provided two relatively spaced elements or pins 62 projecting outwardly from the face 56, these elements being preferably adjustable in slots 64, whereby to accommodate heels of different dimensions and vary the contact thereof with the brush. It will be apparent that the face 56 locates the heel laterally of the brush and the elements 62 locate the heel radially of the brush, whereby the heel may be quickly and accurately polished without the expenditure of undue care 10 and time by the operator. The elements 62 may be removed and only the guiding face 56 used if desired, thus permitting both straight and curved portions of heels to be polished in one operation on the same brush, or the straight portions may be polished on another brush located 15 closely adjacent to the brush employing the stop elements 62.

When it is desired to polish compound heels, such as the heel shown in Fig. 4 and embodying 20 a leather base 66 and a rubber toplift 68, the member 20—21 is adjusted to the position shown in broken lines in Fig. 4. In such position both brushes are exposed forwardly of the face 56. When the heel is placed against this face and 25 contacted with the brushes, the leather portion contacts with the brush 16 and the rubber portion contacts with the brush 18. Thus the leather portion of the heel is polished by the relatively light brush 16 simultaneously with the 30 cleaning and polishing of the rubber portion by the heavier brush 18. The economy and advantages of thus performing these two operations simultaneously will be obvious.

In Fig. 5 I have shown the application of the 40 guide to a single brush 70. The member 20—21 may be used with or without the elements 62 and may be adjusted laterally of the brush to any desired position for exposing such portion of the brush forwardly of the face 56 as is required 45 to perform the polishing operation.

In some cases it is desirable to give two polishing effects to adjacent sections of a heel and to leave a definite line of demarcation between such sections, such heel being either with or without 50 a separate toplift. In Fig. 6 I have illustrated a modified form of the invention particularly adapted to perform this function. This apparatus comprises an arbor 72 having two relatively adjacent bristle supporting means or members 74 mounted thereon and respectively carrying bristles 76 and 78 of different character and similar to the bristles 16 and 18, already described. The members 74 are carried on a bushing 80 of two diameters having an annular shoulder 82 at 55 their junction. Mounted on the smaller portion of the bushing is a metallic member having a hub portion 84 and a disk-like portion 86, collars 87 and 88 holding the members tightly together on the bushing along with the metallic member. The 60 disk portion 86 of the metallic member extends outwardly between the members 74 and its peripheral portion is bent laterally at 90 to engage the inner side face of the bristles 78. This engagement holds the bristles concentrated along a 65 definite line or edge whereby the line of engagement of the bristles 78 with the heel is definite and relatively sharp as contrasted to that portion engaged by the bristles 76. Thus when a heel 70 is polished by the brushes 76 and 78, as illustrated in Fig. 6, the toplift portion engaged and

polished by the brush 78 will stand out as a portion sharply distinct from the portion polished by the relatively softer brush 76.

Having thus described my invention, what I claim as new and desire to secure by Letters Pat- 5 ent is:

1. In a heel polishing machine, two rotary brushes located adjacent to each other on a common axis and respectively having bristles of such different stiffness as to adapt the brushes to act 10 on leather and rubber heel lifts respectively, a member having a face disposed radially outward of the periphery of the brushes and adapted to act as a stop to movement of a heel laterally of the brushes, and means mounting the member for adjustment of said face laterally across the periphery of the brushes.

2. The machine defined in claim 1, plus means rotating with the brushes and engaging against the inner side face of one of the brushes to hold 20 the bristles thereof concentrated along a definite line adjacent to the other brush.

3. In a heel polishing machine, two rotary brushes of substantially equal diameters and located directly adjacent to each other on a common axis, the two brushes respectively having bristles of such different stiffness as to adapt the brushes to act on leather and rubber heel lifts respectively, a member having a face disposed 25 radially outward of the periphery of the brushes and adapted to act as a stop to movement of a heel laterally of the brushes, and means mounting the member for adjustment of said face laterally across the periphery of the brushes. 30

4. In a heel polishing machine, a rotary brush, 35 means carried thereby and engaging against one side face of the brush bristles adjacent to the periphery thereof in a manner holding the bristles concentrated to a sharply defined edge along the side thus engaged, a member located adjacent to the periphery of the brush and having a face disposed to act as a stop to the movement of a heel laterally of the brush and said edge, and means for adjusting the member laterally of the brush and said edge, the member being in 40 all operative positions thereof free from contact with the brush.

5. In a heel polishing machine, a rotary brush, a member having a face disposed radially outward of the periphery of the brush and adapted 50 to act as a stop to movement of a heel laterally of the brush, means mounting the member for adjustment of said face laterally across the periphery of the brush, and a pair of relatively 55 spaced elements carried by the member and projecting outwardly from said face to act as stops for a heel radially toward the brush, said elements being located adjacent to the periphery of the brush and being adjustable in the member toward and from each other to vary the gap 60 therebetween.

6. In a heel polishing machine a frame, a rotary brush supported thereon, an arm supported on the frame rearwardly of the rotary axis of the brush and extending transversely thereof to a point forwardly of said axis, a member carried on the forward end of the arm and having a heel guiding face disposed at the periphery of the brush, and manually operated means for adjusting the member on the arm longitudinally of said axis and said face transversely across the periphery of the brush, the arm being longitudinally adjustable whereby to space the member in the desired relation to the brush. 65

7. In a heel polishing machine a rotary brush, 70

means located laterally of the brush and providing a guideway, a member having a shank portion supported in the guideway and a T-shaped portion at its forward end disposed radially outward of and adjacent to the periphery of the brush, the forward face of said T-shaped portion providing a heel-engaging stop and the member being adjustable in the guideway to

move said face transversely across the periphery of the brush, and a pair of elements carried by the member and projecting outwardly from said face in such relatively spaced relation as to permit the curved portion of a heel engaged with the elements to project therebetween and have limited contact with the brush.

5 WILLIAM P. EGAN.
